(57) **CLAIM**

The ornamental design for a suction storage bin, as shown, and described.

DESCRIPTION

FIG. 1 is a perspective view of a suction storage bin;

FIG. 2 is a front view thereof;

FIG. 3 is a rear view thereof;

FIG. 4 is a right elevation view thereof, the left elevation view being a mirror image thereof;

FIG. 5 is a top plan view thereof; and,

FIG. 6 is a bottom plan view thereof.

The broken lines shown in the figures represent portions of the suction storage bin that form no part of the claimed design.
